(57) **CLAIM**

The ornamental design for a foldable wireless charger, as shown and described.

DESCRIPTION

FIG. 1 is a perspective view of the foldable wireless charger showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the foldable wireless charger is folded.

The broken lines in the figures illustrate portions of the foldable wireless charger that form no part of the claimed design.
